UNITED STATES PATENT OFFICE.

CALVIN L. GODDARD, OF NEW YORK, N. Y.

SELF-FEEDER FOR CARDING-MACHINES.

SPECIFICATION forming part of Letters Patent No. 295,243, dated March 18, 1884.

Application filed May 3, 1883. (No model.)

To all whom it may concern:

Be it known that I, CALVIN L. GODDARD, of the city and county of New York, in the State of New York, have invented a new and useful Improvement in Self-Feeders for Carding-Machines, of which the following is a specification.

My invention relates to self-feeders or self-feeding apparatus for carding-machines in which the wool or other fibrous material is raised from a bin by an endless lifting-apron provided with teeth, which catch hold of the wool or material brought in contact with them, and carry upward what adheres to or is caught by them. When the wool or material reaches the upper part of the bin, the loose hanging locks are struck back or detached by a rotary cylinder or comb, and what is retained by the teeth of the apron is carried over and delivered by suitable mechanism to the carding-machine. Sometimes, in addition to the lifting-apron, an endless apron is arranged to travel in a nearly horizontal direction in the bottom of the bin, so as to carry the wool or material toward and against the lifting-apron, but the horizontal apron has no teeth. The teeth on the lifting-apron are commonly secured from one and a half to three inches apart, or thereabout, in slats which are themselves fixed across the apron from one to two inches apart, and when thus arranged the teeth carry up the long locks or stock most readily, while the shorter stock is apt to drop off and back into the bin. Therefore when coarse and fine or long and short stock are mixed together in the bin for a blend for cards, the coarser or larger stock will be carried upward and delivered to the carding-machine in greater quantity than the finer or shorter stock, and effects a selection of stock which prevents the blend desired. If there be added to the blend more short stock than is wanted for the purpose of causing the apron to take up the desired amount, no dependence can be placed upon the proportions, the blend is useless, and the value of the self-feeder is destroyed. An important object of my invention is to remedy this defect.

The invention consists in the combination, with a bin for stock, of a lifting-apron provided with rows of teeth, and receptacles or

buckets interposed between the teeth, and mechanism for operating said apron and for delivering the material raised by said apron to a carding-engine or other machine. 55

The invention also consists in the combination, with a bin for stock, of an endless lifting-apron provided with buckets or receptacles for raising the stock, a beater or other stripping device near the upper end of the apron, for knocking large locks or bunches of material back into the box, mechanism for operating said beater or stripping device, and mechanism whereby the material raised by the lifting-apron may be delivered to a carding-engine or analogous machine. 65

The invention also consists in a combination similar to that above recited, but including a lifting-apron comprising rows of teeth arranged in the ordinary way, and buckets or receptacles interposed between the rows of teeth. The buckets may be composed of teeth closely arranged, or of sheet metal or other material provided with serrated upper edges, which form teeth for catching and carrying up 75 the larger stock, while the shorter stock is carried up by or in the buckets or receptacles.

In the accompanying drawings, Figure 1 is a vertical section of a feeder or feeding apparatus embodying my invention. Fig. 2 is a front view of the apparatus with the bin broken away, and Fig. 3 is a perspective view of a portion of the lifting-apron. 80

Similar letters of reference designate corresponding parts in the several figures. 85

A designates the bin for wool or other stock, and B designates an endless apron, which is employed for elevating the stock from the bin.

The bin may be of any suitable shape; but preferably its front side slants inward toward the lower end of the apron B, and comprises doors A', which may be opened to afford access to the interior mechanism and for filling the bin. When of the shape shown the stock will be caused to gravitate toward the apron 95 as the supply diminishes, and an apron in the lower part of the bin for moving the stock toward the apron B is therefore unnecessary.

The apron B may be arranged in any suitable position; but, as here shown, it is arranged in an inclined position, and is supported by lower and upper rollers, a a'. The 100

bearings *b* of the lower roller, *a'*, are adjustable, and by means of bolts *b'* may be drawn down to apply tension to the apron and cause it to work properly.

5 As here shown, the belt is provided with rows of teeth *c* and buckets or receptacles *d*, placed intermediately between said rows of teeth. The teeth *c* may be inserted in slats secured to the apron as the teeth of lifting-aprons for card-feeders are ordinarily secured. The buckets or receptacles *d* may be made of teeth secured very near together, so as to form such buckets or receptacles; or they may be made of sheet metal stamped or pressed into 15 the proper shape by means of dies, and secured to the apron *B* by rivets or otherwise. A portion of the apron and its buckets or receptacles are shown in Fig. 3, from which their construction may be more clearly understood. 20 If desired, the edges of the buckets or receptacles may be serrated to form teeth *d'*. (Shown in Fig. 3.)

C designates a beater arranged near the top of the apron *B*, and in such close proximity thereto as to just clear the teeth *c* and buckets or receptacles *d* in rotating. This beater may be of any suitable construction. As here shown, it consists of a wood or metal roll, *e*, having lags or strips *e'* secured upon its surface, and wings or blades *e''*, of sole-leather, which are securely pinched or clamped between the lags or strips *e'*. The teeth *c*, upon the lifting-apron, carry up the long locks of wool, while the shorter stock is carried up by 30 the buckets or receptacles, and the beater *C* is revolved in the direction of the arrow at whatever speed may be necessary to carry back the overhanging locks of wool, but not fast enough to drag the wool out of the buckets or receptacles.

40 I do not limit myself to the alternate arrangement of the buckets or receptacles *d* and teeth *c*, as they may be arranged in other relations to each other; nor do I desire to limit myself to the buckets or receptacles only in combination with the teeth *c*, as in some cases the buckets or receptacles may be used alone, especially if they have toothed edges *d'*. These buckets or receptacles and interposed rows of 45 teeth *c* will carry upward both long and short stock without any selection, and will produce a uniform mix or blend to be fed to the carding-machine.

55 The beater *C*, in lieu of the construction here shown, may consist of a wood roll with teeth set into it fine enough to beat back the overhang from the buckets *d* and teeth *c*; or it may be a reciprocating comb or a roll set with bristles.

60 One advantage of slanting the apron *B* forward is that the wool when delivered at the upper end will fall perpendicularly and away from the apron, so as not to fall down into the bin behind the apron.

65 In lieu of the rotary beater *C*, I may employ a reciprocating comb or other device for strip-

ping the overhang from the lifting-apron. The stock falls from the apron upon a fluted or grooved roll, *D*, and by said roll is delivered onto a grating, *f*, over which it is spread, and carried forward by a revolving beater or cylinder, *E*, which may be a toothed roll, a brush, a shaft with radial wings or blades, or any other suitable rotary device.

Just at the lower end of the grating *f* is arranged the final-feed roll *F*, and its companion rollers *g*, *g'*, *h*, and *i*. The roller *g* is a lap-roller, and as the wool leaves the grating *f* it is delivered by the roller *g'* to the lap-roller *g*, around which it is wound in a perfect, even, and uniform lap. The roller *i*, which is preferably fluted or ribbed, pinches and holds the lap of wool on the lap-roller *g*, while the teeth of the final feed-roll *F* pull it off in even quantities, which are subsequently deposited by the 85 brush *j* upon the feed-belt or other receiving device of the carding-machine.

Motion may be imparted to the several parts by any suitable mechanism. That here shown well answers the purpose.

Upon one end of the shaft of the cylinder or beater *E* is secured a pulley, *k*, over which a driving-belt may be run. To the other end of said shaft is secured a pulley, *k'*, which is connected by a belt, *k''*, with a large pulley, *l*, on the same shaft with a gear-wheel, *l'*. The wheel *l'* engages with a gear-wheel, *l''*, on the shaft of the final-feed roll *F* and drives it, and from this cylinder or roll motion is communicated to the rolls *g*, *g'*, *h*, *i*, as follows: At one end of 100 this shaft a gear-wheel, *l''*, meshes with a pinion, *l'''*, on the roll *i*, and pinion *l''''* meshes with and turns pinion *l''* on roll *h*. At the other end of the machine the shaft of the cylinder or roll *F* bears a pinion, *m*, which engages with pinion *m'* on roller *g'*, and *m'* gears with pinion *m''* on roller *g*.

For driving the beater *C*, a pulley, *n*, is fixed on its shaft, and connected by a belt, *n'*, to a pulley, *n''*, on the shaft of beater *E*, while 110 for driving the brush *j* a pulley, *n'''*, is connected by a belt, *n''''*, to a pulley, *n'''''*, on the shaft of the beater or cylinder *E*, which constitutes the driving-shaft of the machine.

The lifting-apron *B* has its upper carrying- 115 roller, *a*, extended and provided with a pulley, *o*, over which a driving-belt may pass.

What I claim as my invention, and desire to secure by Letters Patent, is—

1. The combination, with a bin for stock, of 120 a lifting-apron provided with rows of teeth, and receptacles or buckets interposed between the teeth, and mechanism for operating said apron and for delivering the material raised by the lifting-apron to a carding-engine or 125 other machine, substantially as specified.

2. The combination, with a bin for stock, of 130 a lifting-apron provided with buckets or receptacles, a beater or other stripping device near the top of the apron, mechanism for operating said apron and beater or stripping device, and mechanism whereby the material

raised by the lifting-apron may be delivered to a carding-engine or other machine, substantially as described.

3. The combination, with a bin for stock, of a lifting-apron provided with buckets or receptacles, and with rows of teeth independent of said buckets or receptacles, a beater or other stripping device near the top of the apron, mechanism for operating said apron and beater or stripping device, and mechanism whereby the material raised by the lifting-apron may be delivered to a carding-engine or other machine, substantially as described.
4. The combination, with a bin for stock, of

a lifting-apron provided with buckets or receptacles having serrated or toothed edges, a beater or other stripping device near the top of the apron, mechanism for operating said apron and beater or stripping device, and mechanism whereby the material raised by the lifting-apron may be delivered to a carding-engine or analogous machine, substantially as described.
